RAIL GUARD

James H. Asselin, Hubbard Woods, Ill., assignor to
 Asselin Crossing Co., San Francisco, Calif., a
 corporation of California

Application October 1, 1938, Serial No. 232,843

8 Claims. (Cl. 238—17)

The present invention has to do with railway track equipment, and more especially relates to rail guards for use in connection with crossings.

It is the primary object of the invention to produce a rail guard of simple character, but strong and sturdy in its structural features so as to afford long life and to be highly resistant to the shocks and stresses imposed by the passage of trains, and particularly those of the present-day high-speed type.

A further object of the invention is to provide a rail guard wherein is embodied highly efficient means for cushioning the structure, whereby to absorb the shocks and jars of traffic and reduce the noise incident thereto.

Other objects and advantages will appear as the nature of the improvements is better understood, the invention consisting substantially in the novel construction, combination and arrangement of parts hereinafter fully described, illustrated in the accompanying drawing, and finally pointed out in the appended claims.

The form of the invention herein shown and described is considered as a practical embodiment thereof and expresses a concrete adaptation of the invention to the uses and purposes for which it is intended. The invention, however, is susceptible to change, modification and variation so that the present disclosure is to be taken from the illustrative standpoint and not as imposing limitation or restriction on the invention.

In the drawing

Fig. 1 is a top plan view of a rail guard constructed in accordance with the present invention;

Fig. 2 is a vertical transverse sectional view, as on the line 2—2, Fig. 1.

Referring now in detail to the accompanying drawing, the numeral 10 designates a base plate which is of rectangular formation, relatively long to meet the purposes for which it is intended, and of uniform width. It is preferably formed of rolled steel. In the practical use of the herein-described rail guard the plate 10 is spiked to the rail ties, as indicated at 11, or otherwise held in place in the track structure.

An inclined bracing flange 12, also preferably of rolled steel, extends longitudinally of the base plate 10, being disposed thereon at the inner edge of said plate 10 as the rail guard is incorporated in the track structure. The bracing flange 12 is a continuous length thereof and has its lower basal edge in contact with the plate 10 and welded thereto, as by seams 13, thus rigidly affixing the flange 12 to the plate 10.

At the upper edge of the bracing flange 12 it is provided with a vertical contact face 14, and this face 14 is designed to be contacted by one side of the head of a guard rail 15 in order to take up the lateral thrust that may be imposed upon said guard rail.

The numeral 16 designates a running rail which is seated also upon the base plate 10, but in spaced relation to the guard rail 15, and interposed between the rails 15 and 16 is a filler block 17 the upper and lower faces of which are grooved to provide flange ways 18. The upper flange way 18 receives the flanges of the car wheels as they pass over the running rail 16.

A plurality of the filler blocks 17 is employed in order to maintain the separation of the rails 15 and 16 throughout the length of the guard and preserve the gauge of the flange ways.

The filler blocks 17 conform to the shape of the rail heads, their webs and the base flanges thereof. In order to maintain the filler blocks 17 in associated relation with the guard rails 15, and to tie the latter to the bracing flange 12, each of the filler blocks is provided with a plurality of transverse bolt openings 19, these openings registering with similar openings 20 formed in the web of the guard rail 15, and said openings 20 likewise register with bolt openings 21 that are formed in the bracing flange 12. A plurality of tie bolts 22 are seated in the openings 19, 20 and 21, the head of each bolt occupying a countersunk recess 23, which recesses are formed in the sides of the filler blocks 17. In this manner the tie-bolts 22 pierce the filler blocks 17, the guard rail 15 and the bracing flange 12 and tie the filler blocks and the guard rail to the bracing flange 12. The threaded shanks of the bolts 22 project beyond the openings 21 of the bracing flange 12 and have fitted thereto fastening nuts 24. A bearing head 25 surrounds each of the openings 21, its outer face being vertical, and thus presenting a square surface, and between said bearing heads 25 and the fastening nuts 24 lock washers 26 are arranged. The bearing heads 25 are secured to the bracing flange 12 by welding, as at 27.

The bases of the guard rail 15 and the running rail 16 are seated upon an elastic cushion 28, preferably in the form of a rubber pad, which cushion is arranged upon the base plate 10 so as to be interposed between the latter and the guard and running rails, and said cushion tapers in cross-section from its outer edge, or that beneath the running rail 16, to its inner edge, or that beneath the guard rail 15. At the outer

edge of the plate 10 is a stop strip 29, which is welded to the base plate 10, as at 30, and this strip defines a boundary between which, and the bracing flange 12, a recess is provided for confining the cushioning pad 28. The stop strip 29 also provides reinforced points through which the spikes 11, at the outer edge of the base plate 10, pass.

The rails 15 and 16 are mounted in canted relation to the base plate 10, and the tapering cross-section of the cushion 28 serves to maintain the rails so canted. Thus, as the beveled treads of the car wheels pass over the head of the running rail 16 they contact the surface of this head so that the metal of the rail head is prevented flowing off due to uneven contact or engagement of the wheel treads with the rail head.

The ends of the guard rail 15 are beveled and flared, as at 31, and the outer ends of the filler blocks 17 which are immediately contiguous thereto are also flared, as at 32. Thus the wheel flanges are guided into the flange way between the heads of the rails 15 and 16 and assured of proper contact with the running rail 16.

At the inner side face of the bracing flange 12 the same is provided with a plurality of lateral inclined bracing struts 33, these being connected to the base plate 10 by welding, as at 34. They serve to reinforce the bracing flange 12 in resisting the lateral thrust imposed upon the bracing flange 12 by pressure of the guard rail 15.

When the herein-described rail guard is incorporated in a track structure, it is apparent that as the car wheels pass over the running rail 16 any lateral thrust of such rail will be transmitted through the filler blocks 17 and the guard rail 15 to the inclined bracing flange 12, but resisted by this flange and the bracing struts 33. The strains and stresses, as well as the shocks, will be taken up by the pad 28, and the base plate 10 relieved of such strains and stresses. Furthermore, the noise incidental to the passage of traffic will be substantially reduced due to the sound-insulating effect of the pad 28.

By use of the stop strip 29 in cooperation with the bracing flange 12 the guard rail 15 is held in position against lateral thrust that may be imposed on the guard rail by pressure from the wheel flanges, and inasmuch as the stop strip 29 engages the base of the running rail 16 and thereby ties the same into assembly with the guard rail 15 there is no displacement of the running rail and pressure that may be exerted against the running rail from the guard rail is effectually resisted.

In the assembled relation of the filler blocks 17, the guard rail 15, the bracing flange 12 and the tie-bolts 22, there is formed a substantially rigid structure which serves to prevent rotational movement of the running rail 16 with respect to the guard rail. The stop strip 29 and this rigid structure also provide means for restricting movement of the running rail 16 laterally with respect to the guard rail 15 but permits longitudinal movement of the running rail 16. The strip 29, combining with the rigid structure, maintains the aforesaid relation of the running rail to the guard rail.

I claim:

1. A rail guard, comprising a base plate, a continuous bracing flange fixedly mounted thereon, a running rail also mounted on said base plate and spaced from said bracing flange, a guard rail also mounted on said base plate adjacent to the bracing flange and in contact with the latter,

filler means interposed between the guard rail and the running rail, means for tieing said filler means, said guard rail and said bracing flange in assembled relation to form a substantially rigid structure, said structure serving to prevent rotational movement of said running rail with respect to the guard rail, and means for restricting movement of the running rail laterally with respect to said guard rail including the aforesaid rigid structure but permitting longitudinal movement of the running rail, said last-mentioned means combining with said rigid structure to maintain the aforesaid relation of the running rail to said guard rail. 5

2. A rail guard, comprising a base plate, a continuous bracing flange fixedly mounted thereon, a running rail also mounted on said base plate and spaced from said bracing flange, a guard rail also mounted on said base plate adjacent to the bracing flange and in contact with the latter, 10 filler means interposed between the guard rail and the running rail, means for tieing said filler means, said guard rail and said bracing flange in assembled relation to form a substantially rigid structure, said structure serving to prevent rotational movement of said running rail with respect to the guard rail, and means for restricting movement of the running rail laterally with respect to said guard rail including the aforesaid rigid structure but permitting longitudinal movement of the running rail, said last-mentioned means combining with said rigid structure to maintain the aforesaid relation of the running rail to said guard rail. 15

3. A rail guard, comprising a base plate, a continuous bracing flange fixedly mounted thereon, a running rail also mounted on said base plate and spaced from said bracing flange, a guard rail also mounted on said base plate adjacent to the bracing flange and in contact with the latter, 20 filler means interposed between the guard rail and the running rail, the guard rail and the running rail being canted, means for tieing said filler means, said guard rail and said bracing flange in assembled relation to form a substantially rigid structure, said structure serving to prevent rotational movement of said running rail with respect to the guard rail, and means for restricting movement of the running rail laterally with respect to said guard rail including the aforesaid rigid structure but permitting longitudinal movement of the running rail, said last-mentioned means combining with said rigid structure to maintain the aforesaid relation of the running rail to said guard rail, and a cushioning pad interposed between the guard and running rails 30 and the base plate. 35

4. A rail guard, comprising a base plate, a continuous bracing flange fixedly mounted thereon, a running rail also mounted on said base plate and spaced from said bracing flange, a guard rail also mounted on said base plate adjacent to the bracing flange and in contact with the latter, 40 filler means interposed between the guard rail and the running rail, the guard rail and the running rail being canted, means for tieing said filler means, said guard rail and said bracing flange in assembled relation to form a substantially rigid structure, said structure serving to prevent rotational movement of said running rail with respect to the guard rail, and means for restricting movement of the running rail laterally with respect to said guard rail including the aforesaid rigid structure but permitting longitudinal movement of the running rail, said last-mentioned means combining with said rigid structure to 45 maintain the aforesaid relation of the running rail to said guard rail, and a cushioning pad interposed between the guard and running rails and the base plate and tapering in cross-section conformably with the canting of the rails. 60

5. A rail guard, comprising a base plate, a continuous bracing flange fixedly mounted thereon, a running rail also mounted on said base plate and spaced from said bracing flange, a guard rail also mounted on said base plate adjacent to the bracing flange and in contact with the latter, 65 filler means interposed between the guard rail and the running rail, means for tieing said filler means, said guard rail and said bracing flange in assembled relation to form a substantially rigid structure, said structure serving to prevent rotational movement of said running rail with respect to the guard rail, and means for restricting movement of the running rail laterally with respect to said guard rail including the 70

6. A rail guard, comprising a base plate, a continuous bracing flange fixedly mounted thereon, a running rail also mounted on said base plate and spaced from said bracing flange, a guard rail also mounted on said base plate adjacent to the bracing flange and in contact with the latter, 75

- aforesaid rigid structure but permitting longitudinal movement of the running rail, said last-mentioned means combining with said rigid structure to maintain the aforesaid relation of the running rail to said guard rail, and a plurality of tie-bolts piercing the filler blocks, the guard rail and the bracing flange for tieing the filler blocks and the guard rail to said bracing flange.
- 5 5. A rail guard, comprising a base plate, a continuous bracing flange fixedly mounted thereon, a running rail also mounted on said base plate and spaced from said bracing flange, a guard rail also mounted on said base plate adjacent to the 10 bracing flange and in contact with the latter, filler means interposed between the guard rail and the running rail, means for tieing said filler means, said guard rail and said bracing flange in assembled relation to form a substantially rigid 15 structure, said structure serving to prevent rotational movement of said running rail with respect to the guard rail, means for restricting movement of the running rail laterally with respect to said guard rail including the aforesaid 20 rigid structure but permitting longitudinal movement of the running rail, said last-mentioned means combining with said rigid structure to maintain the aforesaid relation of the running rail to said guard rail, and a plurality of tie- 25 bolts piercing the filler blocks, the guard rail and the bracing flange for tieing the filler blocks and the guard rail to said bracing flange, the filler blocks being provided with countersunk recesses for receiving the heads of said tie-bolts.
- 30 6. A rail guard, comprising a base plate, a continuous bracing flange fixedly mounted thereon, a running rail also mounted on said base plate and spaced from said bracing flange, a guard rail also mounted on said base plate adjacent to the 35 bracing flange and in contact with the latter, filler means interposed between the guard rail and the running rail, means for tieing said filler means, said guard rail and said bracing flange in assembled relation to form a substantially rigid 40 structure, said structure serving to prevent rotational movement of said running rail with respect to the guard rail, means for restricting movement of the running rail laterally with respect to said guard rail including the aforesaid 45 rigid structure but permitting longitudinal movement of the running rail, said last-mentioned means combining with said rigid structure to maintain the aforesaid relation of the running rail to said guard rail, said stop strip cooperating with the bracing flange to prevent displacement 50 of the running rail under wheel flange pressure that may be exerted from the guard rail, said rigid structure and the last-mentioned means permitting longitudinal movement of the running rail.
- 55 7. A rail guard, comprising a base plate, a continuous bracing flange fixedly mounted thereon, a running rail also mounted on said base plate and spaced from said bracing flange, a guard rail also mounted on said base plate adjacent to the 5 bracing flange and in contact with the latter, filler means interposed between the guard rail and the running rail, means for tieing said filler means, said guard rail and said bracing flange in assembled relation to form a substantially rigid 10 structure, said structure serving to prevent lateral movement in one direction and also preventing rotational movement of said running rail with respect to the guard rail, and a stop strip associated with the base plate at the outside 15 edge of the running rail and adapted to engage said edge for tieing the running rail into assembly with the guard rail, said stop strip cooperating with the bracing flange to prevent displacement 20 of the running rail under wheel flange pressure that may be exerted from the guard rail, said rigid structure and the last-mentioned means permitting longitudinal movement of the running rail.
- 25 8. A rail guard, comprising a base plate, a continuous bracing flange fixedly mounted thereon adjacent to one of its edges and provided at its inner face and at its upper end with a vertical contact face, a guard rail mounted on said base plate immediately adjacent to the bracing flange, the 30 head of the guard rail being seated on the bracing flange, a stop strip associated with the base plate at the edge of the latter opposite to the bracing flange, a running rail arranged adjacent to said stop strip and in contact therewith, filler 35 means interposed between the guard rail and the running rail, means for tieing said filler means, said guard rail and said bracing flange in assembled relation to form a substantially rigid 40 structure, said structure serving to prevent rotational movement of said running rail with respect to the guard rail, means for restricting movement of the running rail laterally with respect to said guard rail including the aforesaid 45 rigid structure but permitting longitudinal movement of the running rail, said last-mentioned means combining with said rigid structure to maintain the aforesaid relation of the running rail to said guard rail, said stop strip cooperating with the bracing flange to prevent displacement 50 of the running rail under pressure that may be exerted from the guard rail, and cushioning means interposed between the guard and running rails and the base plate and held therein by the bracing flange and the stop strip. 55
